UNITED STATES PATENT OFFICE

WILLIAM C. MASSLOW, OF FOREST PARK, ILLINOIS, ASSIGNOR OF ONE-HALF TO
AUGUST E. SCHULTZ, OF FOREST PARK, ILLINOIS

BED

Application filed February 6, 1930. Serial No. 426,296.

My invention relates to beds for invalids and has for its general object the provision of a mattress having a displaceable section permitting the patient to have access to toilet facilities without leaving the bed or being moved.

In carrying out my invention I form an opening in the middle of the mattress which is sufficiently large for the purpose and which is normally occupied by a filler which constitutes a section of the mattress, this filler being of the same general construction as the balance of the mattress. For the sake of convenience this filler is controlled by a lever mechanism which may be operated to bring the filler into the opening in the mattress, or out of register with such opening, as desired. A runway carried by a submattress, presently described, is provided beneath the mattress upon which a bed pan or toilet vessel may be moved into register with the opening in the mattress.

The mattress thus far described is otherwise preferably of any usual construction, being deep and yielding readily to adapt itself to the patient. This mattress is carried upon a submattress which is usually made of metal throughout, being inclusive of springs which also impart a cushioning characteristic thereto. This submattress is carried in any usual or preferred way upon the bedstead. It is discontinued at the portion thereof which is vertically beneath the opening in the main or supermattress to provide an aperture therein beneath said opening, means being employed for securely assembling the two mattresses to maintain the openings therein in proper register. The aforesaid lever mechanism is assembled with the submattress to constitute, therewith, a unitary structure which may be supported upon the bedstead, a construction and arrangement which necessitates no modification of the bedstead, all structural changes and additions being in the mattresses that are removably supported upon the bedstead.

The invention will be more fully explained in connection with the accompanying drawings in which Fig. 1 is a side view of the preferred embodiment of the invention; Fig. 2

is a plan view; Fig. 3 is a sectional view on line 3—3 of Fig. 2, on a larger scale; Fig. 4 is a plan view of the mattress, on a smaller scale; Fig. 5 is a sectional view on line 5—5 of Fig. 2, on a larger scale; Fig. 6 is a view from beneath; and Fig. 7 is a view similar to Fig. 5 with parts in changed positions.

The bedstead is of any suitable construction, the one illustrated being made entirely of metal and comprising an upright head frame 1, an upright foot frame 2 and side rails 3 which are assembled with the aforesaid frames in any suitable way. The submattress is inclusive of a bottom frame 4 which is carried by the side rails 3, upwardly extending brackets 5, longitudinal margining slats 6, other longitudinal slats 7 distributed between the slats 6, cross slats 8 and coiled springs 9 which unite the ends of the slats 6 and 7 with the brackets 5. The mid-portion of the submattress is inclusive of a metallic plate 10 having an unfilled opening and to which some of the slats 7, of reduced length, are secured, as indicated most clearly in Fig. 2. The slats 6, 7 and 8, the springs 9 and the plate 10 constitute a spring structure providing a cushion support for the supermattress next described. The supermattress is of any suitable construction, the construction shown being inclusive of one main body portion 11 which is inclusive of ticking and a filler of cotton or hair. The main body portion of the supermattress has an opening therethrough which is normally filled by a filler 12 which is formed similarly to the main portion of the supermattress and which is desirably also supplied with a support in the form of a metallic plate 13 which is hinged to the submattress and upon whose edge a removable filler cover 14 may be snapped, as indicated most clearly in Fig. 3, where I have illustrated snappers 15 of usual form. The plate 13 is supported solely by the spring structure of the sub-mattress as presently described. The filler 12, the opening in the supermattress which receives it, and the opening in the plate 10 of the submattress are preferably somewhat elliptical.

In order that the openings in the two mattresses may be kept in register, I assemble

the same to prevent creepage of the super-mattress upon the submattress. To this end, anchorage straps 17 may be passed about the two mattresses and tightly secured thereto.

5 Two rails 18 extend crosswise of the bed and are secured to the under side of the ends of the plate 10 of the submattress. They may also be suitably secured to other parts of the submattress but are desirably supported solely by the spring structure of the submattress. These rails are spaced apart a distance about equal to the length of the openings in the mattresses and constitute a runway extending beneath said openings.

10 The rails are desirably of Z-form and are so assembled as to present two inwardly projecting ledges upon which the rim of a vessel 19 may be placed. Such vessel has a handle 20 by which it may be moved into register with the openings in the two mattresses or removed from the bed. Before the vessel is placed upon the rails in position beneath said openings, the filler 12 is removed from the opening in the supermattress that it normally occupies. In order that the filler may be conveniently removed and restored I provide operating lever mechanism therefor. The lever mechanism illustrated is inclusive of a link 21 which is pivoted at one

25 end to a bracket 22 which is carried by and depends from the plate 13. The plate 13 is also shown appropriately hinged as at 22a by the hinge members 22b (suitably secured to the plate) to a member 22c carried by and secured transversely of the rails 18. Another link 23 is connected with the link 21, at one end, and is secured at its other end to a rod 24 which is journaled in brackets 25 that are carried by and depend from the rails 18. The

30 link 21 has its lower end upturned and there carries a pin 26 which bears upon the top of the link 23 and normally maintains the center of connection of the two links below a straight line containing the pivotal centers of the links. The connection between these two links thus constitutes a toggle joint which automatically locks the plate 13 in position in the aperture in the plate 10. An arm 27 is also fixed upon the rod 24. One end of the operating arm 28 is pivoted upon the upper end of the arm 27. The arm 27, rotatable rod 24 and link 23 thus constitute a bell-crank, the link 21 being hinged to one lever of the bellcrank, the link 23, and the arm 28 being pivoted to the other lever of the bellcrank, the arm 27. The lower edge of the arm 28 is formed with two notches 29 and 30 which are adapted to receive a retaining pin 31 which is carried by the bracket 32 which is provided upon and depends from one of the rails 18. Thus the plate 13 and lever mechanism connected therewith for the operation thereof are supported solely by the spring structure of the submattress. The arm 28 has a downwardly projecting angu-

lar extension 33 by which it may be manipulated. When the arm 28 is in the position shown in Fig. 5, the filler section 12 of the supermattress is in position. When said arm is moved inwardly to a position in which the notch 30 receives the pin 31, the filler is swung downwardly and sufficiently out of register with the openings in the two mattresses to permit the vessel 19 to be moved into register with such openings and out of register therefrom. The link 21 is desirably a double link whose parts are joined by the pin 26, the single link 23 being received between the lower ends of the two parts of the double link 21 as is clearly illustrated.

70 75 80 Changes may be made without departing from the invention.

Having thus described my invention, I claim:

In a bed for invalids, a sub-mattress adapted to carry a separable super-mattress having an opening therethrough in a mid-portion thereof, said sub-mattress comprising a frame; a spring structure carried by the frame and adapted to provide a cushion support for the super-mattress; an aperture in the spring structure for registering with the opening in the super-mattress; a pair of parallel rails carried by the spring structure and extending transversely of the submattress on each side of said aperture; a filler support pivoted on said spring structure transversely of the rails at one side of the aperture; a filler on said filler support for the opening in the super-mattress; brackets depending from said rails; a rod journaled in the brackets and extending laterally beyond the rails; a link rigidly secured to the rod mid-way thereof and extending upwardly therefrom; another link pivoted to the first link and to the filler support substantially centrally thereof; a lever rigidly connected to one end of the rod and extending upwardly therefrom; an arm pivoted to the upper end of the lever and extending parallel with said rails toward a margin of the sub-mattress, said arm being movable transversely of the sub-mattress; a bracket carried by the sub-mattress for slidably carrying the outer end of the arm; a handle on the arm between the bracket which carries the arm and the margin of the sub-mattress; and a separable vessel slidably supported by said rails.

100 105 110 115 120 In witness whereof, I hereunto subscribe my name.

WILLIAM C. MASSLOW.
